(74) Attorney, Agent, or Firm — Mitchell Law PLLC; Matthew W. Mitchell

CLAIM

The ornamental design for an apron, as shown and described.

DESCRIPTION

FIG. 1 is a front perspective view of the apron of the present invention;

FIG. 2 is a front view of the invention of FIG. 1;

FIG. 3 is a back view of the invention of FIG. 1;

FIG. 4 is a top plan view in elevation of the invention of FIG. 1;

FIG. 5 is a bottom plan view of the invention of FIG. 1;

FIG. 6 is a side view of the invention of FIG. 1, as seen from the left side of FIG. 2;

FIG. 7 is a side view of the invention of FIG. 1, as seen from the right side of FIG. 2;

FIG. 8 is an elevational view of the invention of FIG. 1, as seen with buckles in an engaged position;

FIG. 9 is a second elevational view of the invention of FIG. 1, as seen with buckles in an engaged position; and,

FIG. 10 is a top elevational view of the invention of FIG. 1, as seen with buckles in an engaged position.

The broken lines showing jewels depict parts of the apron that form no part of the claimed design; while the remaining broken lines depict stitching and are included the claimed design.

1 Claim, 6 Drawing Sheets
